UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON-ATTACHING MACHINE.

Application filed February 26, 1925. Serial No. 11,664.

To all whom it may concern:

Be it known that I, FRANKLIN R. WHITE, a citizen of the United States of America, residing at Waterbury, in the county of New Haven and State of Connecticut, have invented certain new and useful Improvements in Button-Attaching Machines, of which the following is a specification.

My invention relates to new and useful improvements in button attaching machines, and in its broadest aspect is similar to the type of button attaching machine shown in Patent 1,079,968, granted to me on December 2, 1918.

15 After using the construction shown in the above numbered patent, I found that it was desirable to provide the escapement for the buttons that would not only operate in the ordinary cycle, but might also be manually operated to feed a single button or successive buttons, and after constructing such an escapement a patent was granted to me for this invention on October 26, 1916, the patent being numbered 1,157,743.

20 Again, I have found that it would be desirable to construct the button attaching machine whereby the tacks or rivets for the buttons would not only be released, in their proper cycle, but wherein similar to the arrangement for the buttons, a tack or successive tacks might also be liberated to the tack receiving jaws by a manual operation independent of the ordinary feeding cycle of the machine.

25 One of the objects, therefore, of the present invention, is to provide an improved feeding and releasing or escapement mechanism for the tacks, so that the tacks will be released to the button receiving jaws at their proper time, and furthermore, should a tack become jammed, or not feed properly the operation of a handle by a manual movement will cause the tack magazine to be revolved, the escapement to be operated, and the tucker mechanism to feed a tack to the tack receiving jaws.

30 In other words, in case the tacks or staples should not feed at their proper rate, the machine is so arranged that a manual operation, without in any way interfering with

the automatic operation, will cause a tack to be fed to the tack receiving jaws.

Furthermore, of course, this tack feeding mechanism when it is manually operated is independent of the button feeding mechanism and throughout the specification it is to be understood that when I speak of the "button attaching means" and "feeding mechanism," I refer to that part of the machine that handles the button head, while the tack feeding mechanism relates to that part of the machine that feeds and releases the tacks which perforate the hub of the button head.

35 The present machine, therefore, contemplates a machine wherein a button may be both automatically released, and manually released, as shown in my previous patent, and also wherein the tacks will be fed at their proper time and in a regular cycle, 40 but at the same time, the tack releasing mechanism, etc., is so designed that a tack or a few successive tacks may be quickly, but manually released to the tack receiving jaws. This will make it possible for the 45 button mechanism and the tack mechanism to be properly synchronized; also to release either a button by hand, or a tack manually thus speeding up the operation of the machine and overcoming any delays which 50 would otherwise be incident.

55 A still further object of the invention is to provide an improved tucker mechanism that will operate with little or no friction, and which will be positively locked against 60 movement during a major portion of the several operations, but at the same time will be instantly released at its proper point in the cycle to force the tack rapidly from the feeding table to the tack 65 receiving jaws, where it (the tack) will be held until it is passed through the perforate button head.

70 Still another object of the invention is to interlock the escapement mechanism with the tucker mechanism so that these two parts will be properly synchronized and may be brought into action either by the ordinary operation of the machine or by a manual operation when so desired.

Still another object of the invention is to also connect the tucker mechanism with means connected to the tack magazine, so that the magazine will be rotated when the tucker mechanism and escapement mechanism operate, this rotation, of course, taking place whether the tucker mechanism is operated automatically or by hand. Thus, should the tack fail to feed, a quick movement of the handle will revolve the magazine, operate the escapement and the tucker mechanism independent of the remainder of the machine, and provide a tack on the anvil so that for every stroke of the plunger, a tack will be present for securing of the button to the garment.

Still another object of the invention is to provide an improved escapement for the tacks or rivets so that the various parts may be readily adjusted to cooperate at the proper instance with the tucker mechanism, and may be adjusted to properly allow for the wear after long and continuous use; and to further arrange the several parts of the escapement mechanism so that if for any reason some of the tacks become jammed, a spring will act as a bumper to take up the resulting loads and thus prevent destruction of the several parts of the tucker and feeding and release mechanism.

Still further objects of the invention is to so arrange the several parts that they will be readily accessible for replacement when worn beyond further usage and to provide ample space between the button attaching zone and the tack or fastening delivery chute, so that the garment to which the buttons are to be secured may be easily and quickly handled to thus facilitate the entire button attaching operation.

Still other objects of the invention are to so arrange the machine and all of its cooperating parts that a complete movement of the oscillating lever will result in a feeding of both the tack and the button, and secure the button to the garment, and at the same time to so arrange the several parts that it will be possible, when necessary, as before mentioned, to feed one or a successive number of tacks manually without a movement of the oscillating lever to provide a tack for every button.

With these and other objects in view, the invention consists in certain new and novel constructions and combination of parts as will be hereinafter more fully described and pointed out in the claims.

Referring now to the drawings showing a preferred embodiment of the invention,

Fig. 1 is a perspective of the improved button attaching machine, the lid over the tucker mechanism being raised to clearly show the same, the several parts of the machine being in their normal position.

Fig. 2 is a side elevation of the machine,

the tack magazine and its cooperating feeding mechanism being removed.

Fig. 3 is a sectional view taken on line 3—3 of Fig. 2 of the button receiving jaws.

Fig. 4 is a sectional view taken on line 4—4 of Fig. 2 showing a part of the mechanism for manually feeding the tack to the tack receiving jaws.

Fig. 5 is a side elevation of a part of the tucker mechanism and a portion of the tack feeding chute and showing the escapement mechanism cooperating with the tucker mechanism.

Fig. 6 is an end view of the tucker mechanism looking in the direction of the arrows on line 6—6 of Fig. 5.

Fig. 7 is a sectional view taken on line 7—7 of Fig. 5.

Fig. 8 is a sectional view of a portion of the tack escapement mechanism.

Fig. 9 is a top plan view of the tack feeding mechanism, and escapement mechanism, and showing the handle for manually operating these parts.

Fig. 10 is a view from the rear showing the means for rotating the tack feeding magazine manually.

Fig. 11 is a view of the lower portion of the tack chute and escapement mechanism, one of the jaws being swung open for the sake of clearness, and the escapement jaws being shown in their operated position.

Fig. 12 is a detailed sectional view taken on line 12—12 of Fig. 11, the arm 41 being in its normal position.

Fig. 13 is a sectional view taken on line 13—13 of Fig. 11, the arm 41 being in its normal position.

Fig. 14 is a fragmentary detailed view showing the lower end of the chute fitting within a guide block on the table, and

Fig. 15 is a fragmentary plan view of the button escapement.

Referring now to Figs. 1 and 2 in particularly, there is shown a metal base 1, from which extends the curved upright arm 2 integral therewith and slotted as at 3, the slot extending from near the base to the upper outer end of the arm where it, in turn, is made to form the bearing 4, in which is placed the bushing 5, and in which operates the die or plunger 6, the latter being slotted at its upper end as at 7 to receive a connecting link 8. The link is pinned at one end in the slot of the plunger as at 9, and at its other end is secured to the outer end of an oscillating lever 10, the latter being fulcrumed as at 11 in the upright arm 2, as may be seen by the several figures.

The lower end of the oscillating lever 10 has the bearing 12 for the reception of a connecting rod (not shown) so that the lever may be oscillated as shown in my previous Patent, No. 1,079,968.

Any desirable form of means for impart-

ing movement to this oscillating lever may be employed. Secured to the upright arm 2, as may be seen in Fig. 1 is a bracket 13 to which is secured the plate or casting 14 which plate contains the magazine 15 for the holding and supplying of the tacks 17 which are adapted to feed down a chute 18 to the table 19 from which they are forced into the tack gripping jaws 20 to be hereinafter more fully described. The jaws and their mechanism are similar to the construction shown in a patent granted to me on July 17, 1924, No. 1,497,819, and need not be explained in detail.

Referring again to the feeding mechanism for the tacks, on the rear of the rotatable magazine 15 there is shown a form of ratchet mechanism 21 operated by a small bell crank 22 so that a movement of this bell crank will cause the magazine to feed step by step, the magazine having the slots 16 therein for the escapement of the tacks as shown in my previous patent.

The bell crank 22 is properly mounted on the undersurface of the plate 14 and is operated by the arm 23 (Figs. 2 and 10), the lower end of the arm being connected to the head 25 mounted on the upper end of the pitman 26 on which is the cross head 27 mounted in the yoke 28 and pressed by the spring 29, the yoke 28 being held in the lower end of a second oscillating lever 30. This oscillating lever 30 is irregular in shape as shown in Fig. 2 and is provided with a slot 31 in which travels the pin 32 fastened to the oscillating lever 10.

The forward end of the pitman 26 is pivotally secured to the horizontal positioned bell crank 33, the pivot being at the point 34.

Before further discussing this bell crank lever 33, and its operation, the movement of the oscillating lever 30 and its functions will be set out. This lever 30 is pivoted at the point 35 on the curved upright arm 2 and as the main oscillating lever 10 is raised it will in turn force the upper portion of the lever 30 in a forward direction, due to the pin and slot connection before referred to, while the lower portion of the lever, that is, the part below the fulcrum point will move rearwardly, thus causing the yoke 28 to pull the pitman 26 rearwardly and through the connecting rod 23 and the bell crank lever 22 the ratchet mechanism 21 will be operated. This action revolving the tack magazine one step to liberate a tack to the tack chute, will be clearly seen. The operation of this oscillating lever 30 also operates the tucker mechanism as will be hereinafter more fully described.

As far as the specification has proceeded, it will be seen therefore that an upward movement of the main oscillating lever will

cause the second oscillating lever 30 in turn to pull the pitman rearwardly, and as this in turn is connected with the ratchet mechanism on the rotatable magazine, it will liberate the tacks to the chute.

Furthermore, an operation of this lever 30 will also operate the tack escapement and the tucker mechanism shortly to be described. As mentioned previously in the specification, it is often desired to feed a tack manually to the tack receiving jaws so that there will be a tack for every button at each stroke of the plunger, and to accomplish this, I have provided a handle 36 which is pivoted as at 37 and extends beneath a cut out portion in the hub 38 of the bell crank 33. The handle engaging with the wall of the cut out portion when swung to a certain position will move the bell crank and at the same time, if the handle does not engage the wall, the handle will remain idle even when the bell crank is operated through the movement of the oscillating lever 30.

A forward movement of the handle 36, however, will cause it to engage with the wall of the cut out portion of the hub and will cause the bell crank to be moved inwardly through the cross head 27 and through the eye yoke 28, and this movement of the pitman through the connecting rod 23 will cause the ratchet mechanism to be operated wholly independent of the oscillating levers 10 and 30, and the spring 29 will return the bell crank 33 to its normal position. The movement of the bell crank will also operate the escapement and tucker mechanism, now to be described.

Tucker mechanism.

Referring now to the tucker mechanism, it will be seen that the base 1 at its forward end is provided with a small block 39 which is positioned directly beneath the chute 18 and on this block is mounted the table 19 heretofore referred to, along which the tack is passed after leaving the escapement (shortly to be referred to), so that the tack will be directly in front of the tucker slide 40 where it will be advanced to the heretofore mentioned tack jaws 20 and securely held directly beneath the plunger or die 6 which forces it through the garment and button.

Adapted to rest on the table 19 is the small arm 41 which is pivoted as at 42 which is provided on its one surface with a wing 43 as may be seen in Figs. 1 and 5, while on the opposite side of the table is a small plate 44, the distance between the wing on the one side of the table and the small plate on the other side of the table forming a slot or space registering with the tack chute 18 so that the tack will be guided or held in its longitudinal path across the table.

The arm 41 is pivoted so that it may be

swung outwardly in case the tacks become jammed. The arm 41 has a cut-out portion 45 extending beneath the wing, as may be seen in Figs. 9 and 11, so that the jaw 46 of the oscillating tack escapement 47 may operate even though the jaw extends below the upper surface of the arm 41. In Fig. 11 I have shown this arm 41 swung to one side, and it will be noticed that located right below the jaw 46 of the oscillating escapement 47 and pivoted to the chute 18 is a small gate 48 which may also be seen in Fig. 1 which is cut out as at 49 so that it may be swung outwardly if the tacks should be come jammed. The inner surface of this gate 48 forms the lower extremity of the chute 18 and is also undercut as at 50 to allow for the thickness of the tack head as it passes from the lower end of the chute to the table.

It might be mentioned that the small plate 44 heretofore referred to, also does not extend flush with the table on its inner side as the tack head must pass under a portion of this plate as well as under a portion of the undersurface of the wing 43. In other words the tack is not only guided across the table by the several walls coming into contact with the prong of the tack, but the head also passes under the lower surfaces of the arms and plate to keep the tack in an upright position. The position of the lowermost tack 17 as shown in dotted line in Figs. 9 and 11, shows how the head fits under the parts just above mentioned.

The oscillating escapement 47 consists of the aforementioned jaw 46 and a jaw 51 which are secured to the block 52 which in turn extends under the chute 18 and pivoted as at 56, the jaws 46 and 51 oscillating across the top surface of the chute 18 from the position shown in Fig. 9 to the position shown in Fig. 11. Extending down one side of the tack chute and parallel with the inner edge thereof, is the guide 52 having the lower end thereof 53 slightly dished so that a tack could be reached by the operator if desired to relieve a jam, and this guide is spaced slightly above the upper surface of the tack chute so that the jaw 51 may operate between the undersurface of the guide and the upper surface of the chute.

The one jaw 51 has the toe 54 at its lower end, while the jaw 46 has a point 55 formed to extend just in front of the toe 54 of the other jaw, and also has the small hook 56 at its lower end so that as the escapement oscillates across the chute it will liberate the tack from in front of the point 55, and the toe 54 will retain the tack until the escapement is again oscillated, this time the tack being caught by the hook 56. Again, as the escapement oscillates, the hook is withdrawn and the tucker slide 40 will

force the liberated tack across the table between the aforementioned plate 44 and the wing 41 directly into the jaws 20 heretofore mentioned.

These tack receiving jaws are pivotally mounted on a spring-pressed anvil 21, which anvil fits within an opening in a base 1, as may be seen from several of the views, and is somewhat similar in construction to one of the above mentioned patents. Its specific construction does not form a part of the present invention and any desired form of tack receiving jaws and anvil might be used.

Referring now more specifically to the tucker slide 40, it will be seen that it is substantially in the shape of an inverted T as may be seen in Figs. 6 and 7 and at the forward end is provided with a pin 57 which is engaged in a slot 58 in the end of the bell crank 33.

The tucker slide 40 travels in a casing 59 the forward end of which is mounted on the block 39, the casing and block and table 19 being so arranged that as the tucker slide passes beneath the lower end of the chute 18, it will advance directly along the table and feed the tack as heretofore mentioned. This casing 59 has a cut out portion 60 therein in the shape of an inverted T, as may be clearly seen in Figs. 6 and 7, to thus hold the tucker slide from wobbling or canting during its operation. Formed at the rear of the slide is the arm 61 which extends downwardly and in which is mounted the short arm 62 on which is mounted the rollers 63 which are adapted to engage with the under surface of the casing 59 to also prevent the tucker slide from canting, while a set screw 64 is mounted at the rear end of the arm, as may be seen in Fig. 5, so that this screw will contact with the rear of the block 39 to limit the forward motion of the slide.

I have also provided a lock for the escapement mechanism, which lock cooperates with the tucker mechanism so that the escapement mechanism will be held against movement except at the proper period, this lock comprising a bell crank 65 mounted as at 66 to the casing 59 of the tucker mechanism, this crank having the locking finger 67 and the hook portion 68 which partly encircles one of the rollers 63 at certain periods as may be clearly seen in Figs. 1 and 5.

Also integral with the block 39 is the small supplemental guide finger 69 so that when the two fingers 67 and 69 are in parallel relation, the cam surface forms a straight line and one of the rollers 63 will travel along the undersurface of the cam finger 67 and against the lower portion of the casing. Supposing the oscillating lever 10 to be in its

normal position, then the tucker slide will be in its foremost position, as may be seen in Fig. 1, and one of the rollers 63 will engage the finger 67 of the tucker slide, thus holding the escapement mechanism against movement, as will be shortly described. On the raising of the oscillating lever 10, the bell crank 33 through the pitman 26 will be operated, and the pin 57 in the slot in the bell crank lever will force the tucker slide rearwardly, the roller 63 moving along the cam surface of the locking finger 67, acting as a positive lock upon the rearward stroke of the tucker until the roller strikes against the hook 68 and passes beyond the center of the crank 65, thus releasing this finger 67 and causing an arm 70 of the bell crank to move downwardly to operate the tack escapement mechanism as will be now described. Thus, it will be seen that by forming the tucker mechanism as shown, the friction is greatly lessened, the tucker is prevented from canting or tipping and acts as a positive lock and as a positive operating means for the tack escapement.

Referring now to the operating of the tack escapement through the movement of the arm 70, which it will be remembered is operated by a movement of the tucker slide, there is shown in Figs. 5 and 8 a bearing 71 secured on the casing of the tack escapement mechanism 14 in which is mounted a sleeve 72 through which extends the push rod 73 threaded for the reception of the nuts 74, this rod extending to a bearing 75 secured to the undersurface of one side of the escapement block 52, which block, it will be remembered, has secured thereto the jaws 51 and 46, as may be seen in Fig. 9. The bearing 75 is pivotally fastened to the block 52 by the stud 77 as may be seen in Fig. 8, a pivotal connection being necessary due to the oscillating movement of the escapement mechanism.

Slidably mounted on the rod 73 is the head 78 having the two flattened portions 79 which are engaged by the enlarged bifurcated ends 80 of the arm 70 of the crank 65. A collar 81 is also mounted on this rod 73 which is held against the flattened portions 79 of the head 78 by the spring 82, the opposite end of the spring pressing against the bearing 75.

This mechanism is very important as it provides means for adjustments for wear on the several parts and also makes it possible to synchronize the stroke or to bring it back to its proper place with the other operating part. A forward movement of the arm 70 will cause the ends 80 through the collar 81 to force the rod 73 downwardly which in turn will oscillate the escapement across the chute and the continued downward movement of the arm will compress the spring

82, allowing the collar to move downward, 65 slightly from the head 78, thus providing for the full rearward movement of the tucker mechanism, and the downward plunge of the die 6 and at the same time relieving the strain on the escapement mechanism. 70

The downward stroke of the oscillating lever 10 which in turn causes the tucker slide to move forwardly, will move the arm 70 of the crank 65 upwardly, thus oscillating the escapement through the ends 80 contacting with the head 78 and moving it upwardly. By moving the adjusting and locking nuts 74, the sleeve 72 bearing against the head 78 may be adjusted in this manner 80 to take up for the wear or synchronization of the stroke, it being possible to adjust this sleeve so that the jaw of the tucker mechanism may be set at any point from its one position across the chute to its other. 85

In this manner the escapement of the tack may be absolutely synchronized with the movement of the tucker slide so that there will always be a tack released and in front of the tucker slide when the tucker slide is 90 about to move forwardly.

Referring now briefly to the mechanism for receiving the buttons from the magazine and chute, there is shown the arm 90 which is pivotally secured as at 91, the forward portion of the arm 92 extending in an angular position on which is secured the jaws 93 which extend directly under the plunger 6. A supplemental pair of jaws 94 are shown for preventing the button from rebounding or being forced out of the jaws 93, and this button-receiving mechanism is mentioned here only briefly as it forms the subject matter of a separate application about to be filed. 105

In Fig. 1 there is shown a support 95 to the upper end of which is secured the rotatable magazine 96 for holding and supplying buttons which is provided with a ratchet mechanism at its rear (not shown) which ratchet mechanism is operated by the rod 97 secured to the main operating lever 10 and the buttons fed down a chute 98 to the button receiving jaws 93, an escapement 99 being provided for the buttons, as shown in my previous Patent, No. 1,157,743 of October 26, 1915, and in Fig. 15. 110

It will be seen that the various steps in the operations are automatically and primarily controlled by the operation of the oscillating lever 10, while several of the parts may be also operated manually when desired. 120

Inasmuch as there are a number of synchronized and cooperating movements, a reiteration of the various operations will be set out, first taking up the operation when controlled by the regular movement of the 125

oscillating lever 10; and second, when the operations are performed manually.

Operation.

5 Presupposing that the oscillating lever 10 is in its lowermost position, as shown in Fig. 2, and the button within the button receiving jaws 93 and the tack 17 on the anvil and within the tack receiving jaws 20, 10 the tucker slide 40 will be in its forwardmost position, as fragmentarily shown in Fig. 2. The garment will be placed under the button receiving jaws and means (not shown) will be set in motion to start the 15 oscillating lever 10 in its upward movement, which, through the rod 97 will rotate the button magazine 96 to feed another button to the chute 98.

At the same time, the raising of this oscillating lever will start the plunger 6 downwardly to force the button downwardly on the tack or rivet, and cause the latter to perforate the garment and the imperforate head of the button and thus lock the button 25 head to the garment.

Also, the upward movement of this oscillating lever through the pin 32 will force the lower end of the oscillating lever 30 rearwardly, and by the pitman 26 and the bell crank lever 33, the tucker slide 40 will move rearwardly, as this tucker slide is operated by the pin 57 within the slot 58 of the bell crank lever 33. The escapement, it will be remembered, for the tack, will be 35 locked, as shown in Fig. 1, as one of the rollers 63 will be against the cam surface of the locking fingers 67, which is a part of the crank 65, as well as the arm 70, the movement of the latter oscillating the escapement 40 47 across the chute.

As the oscillating lever 10 continues to ride, the pitman 26 will continue to be pulled rearwardly and the arm 23 will move upwardly to operate the ratchet mechanism 21 45 mounted on the rear of the tack magazine 15. By the time the plunger 6 has forced the button nearly against the tack point, one of the rollers 63, mounted at the rear of the tucker slide, will engage the hook 50 68, so that the crank arm 65 is now ready to be moved beyond its center. As the finger 67 may swing downwardly, the escapement is in an unlocked position, that is, the arm 70 is now free to be moved downwardly to 55 oscillate the escapement 47. A continued upper movement of the lever 10 forces this tucker slide rearwardly, and the finger 67 now being free to move downwardly, the movement of the roller causes the hook 68 60 to operate the crank 65, in turn causing the jaws 46 and 51 of the escapement 47 to assume the position shown in Fig. 11, the tack having now moved to the lowermost position shown in Fig. 11 and held by the finger 65 65 56. This oscillating movement, of course,

is caused by the ends 80 of the arm 70 forcing the rod 73 downwardly to operate the escapement, as has been heretofore mentioned.

The final upward movement of the lever 10 will lock the button and tack in their final positions to the garment, after which the oscillating lever 10 at its rear end will be started downwardly. This downward movement causes the plunger 6 to rise, together with the button receiving jaws, and as the pitman 26 now moves forwardly, the bell crank 33 will be moved in an opposite direction to that first mentioned, that is, will assume its normal position, and start the tucker slide forwardly. The roller 63 will force the cam finger 67 to a horizontal plane, and at the same time move the arm 70 of the crank 65 upwardly to again oscillate the escapement jaws across the tack 75 chute 18. This oscillation of the jaws will now leave the tack in front of the tucker slide, it being liberated from the finger 56, and as the oscillating lever 10 is continued in its downward movement, the tucker slide 80 will force and guide the tack 17 across the table 19, it being held on its opposite side by the plate 44 and the wing 43 of the arm 41, finally forcing the tacks into the tack receiving jaws 20.

While the oscillating lever 10 has been moving downwardly and the tack forwardly, the ratchet mechanism of the tack magazine is being operated, and the ratchet mechanism of the button magazine is also being 90 operated.

The downward movement of the oscillating lever 10, of course, pulls the plunger 6 upwardly and lets the pivotal arms 90 with the jaws 93 move upwardly and also operates the button escapement mechanism 98 so that another button will be in the button receiving jaws to receive the downward movement of the plunger at the succeeding upward stroke of the oscillating lever 10. 105

This is the cycle of the machine when operated by power, and if for any reason the tacks should become jammed, and not be liberated by the oscillation of the escapement mechanism, it will only be necessary to operate the handle 36, that is, pull it forwardly so that it will engage the wall 37 of the hub 38 of the horizontal bell crank 33 and through the operation of the pitman 26 and the pin 57 working in the slot 58 of the bell crank lever 33, the tucker slide will be pulled rearwardly, and, after it has reached a certain point, as heretofore described, the escapement mechanism will be oscillated, 115 and the tack magazine rotated. The spring 29 will now force the bell crank 33 to its normal position, as the pitman will ride through the cross head in the yoke, and its movement through the various cooperating parts will oscillate the escapement mecha- 120 125 130

nism and force the tucker slide again forwardly, forcing the tack across the table into the tack receiving jaws.

Thus it will be seen that the various parts are so arranged that the feeding of the tacks and the feeding of the buttons will be properly synchronized, but should for any reason the tacks not flow as they should, the operator may simply grasp the small handle 36 and operate it a couple of times to thus feed a tack or tacks to the jaws 20, so that there will always be a tack for each button. This may all be accomplished very quickly, so that there will be no time lost in the attaching of the button.

Furthermore, it will be seen that the tucker mechanism and the escapement mechanism, are so arranged that they are interlocked at certain times or periods, the escapement mechanism being locked until the tucker slide has moved for a certain distance in its rearward travel, and locked throughout the forward movement of the slide.

Again, the oscillating escapement mechanism across the chute may be adjusted or timed by the set and lock nuts on the rod 73 while the wear on the several parts may be also taken up by the adjusting of the same nuts.

Also, by arranging the tucker mechanism as shown, not only is the escapement locked in certain relation with the tucker mechanism, but the tucker slide is held rigidly against canting or tipping throughout its travel, which is very desirable, as if the tacks become jammed at the mouth of the chute, a relatively heavy load is thrown on this tucker slide.

By providing the little table 19 as shown, and the small arms located thereon, the line of the tack movement may be easily reached or in other words, is readily accessible and an offending tack may be readily removed. By providing the pitman and spring in connection with the bell crank lever 33, the tack escapement and tucker mechanism may be operated independently of the ordinary cycle of the machine, the spring returning the parts to their forward position, and likewise by providing a spring operating on the rod 73 connected to the oscillating escapement, the escapement may be carefully regulated and the mechanism relieved from sudden jars or destruction.

Although I have not described the escapement mechanism for the buttons, this is shown in one of my previous patents, and with this escapement attached to the machine, it will be possible to manually release a button and to manually release a tack.

The machine is one which has proved very efficient in service, saving much time over the former machine and may be operated at a relatively high rate of speed.

It will be understood that I have shown a preferred embodiment and construction, and that many slight changes might be made without in any way departing from the spirit and scope of the invention.

Having thus described my invention, what I claim as new and desire to secure by Letters Patent is:—

1. In a button attaching machine, a plunger, means for operating the same, means for feeding the buttons to the plunger, tack-receiving jaws located beneath the plunger, a rotatable hopper for the tacks, means for automatically rotating the hopper and feeding the tacks to said tack receiving jaws normally controlled by said plunger actuating means, and means independent of said plunger actuating means for manually operating said automatic tack feeding means and rotating said tack hopper to thereby feed a tack to the tack receiving jaws.

2. In a button attaching machine, a plunger, means for operating the same, a rotatable hopper for holding the buttons, means for rotating said hopper and means for feeding the buttons to the plunger controlled by said plunger actuating means, tack receiving jaws located beneath the plunger, a rotatable hopper for the tacks, means for automatically rotating the hopper and feeding the tacks to said tack receiving jaws normally controlled by said plunger actuating means, and means independent of said plunger actuating means for manually operating said automatic tack feeding means and rotating said tack hopper to thereby feed the tack to the tack receiving jaws.

3. In a button attaching machine, a plunger, an oscillating lever for operating the same, an escapement for allowing the buttons to pass to the plunger and normally controlled by said oscillating lever, said escapement capable of being manually operated, tack receiving jaws located beneath the plunger, means for automatically releasing the tacks to said tack receiving jaws and normally controlled by said oscillating lever, and means independent of said oscillating lever for manually operating said automatic tack releasing means to thereby feed a tack to the tack-receiving jaws.

4. In a button attaching machine, a plunger, an oscillating lever for operating the same, a rotatable hopper for the buttons provided with a chute, an escapement on said chute for allowing the buttons to pass to the plunger, said rotatable chute and said escapement being normally controlled by said oscillating lever and said escapement being capable of manual operation independent of the oscillating lever, a tack magazine provided with a chute, tack-receiving jaws located beneath the plunger,

an escapement for the tacks, said escapement and said tack magazine being normally controlled by said oscillating lever, and means manually operable independent of the movement of the said oscillating lever for operating the tack magazine and the said escapement to thereby feed a tack to the tack receiving jaws.

5. In a button attaching machine, a plunger, a rotatable hopper provided with a chute for the reception of the button heads, an oscillating lever for operating said plunger, a reciprocating escapement on said chute, said oscillating lever actuating said hopper and reciprocating said escapement and said escapement being capable of manual operation independently of said oscillating lever, a rotatable tack magazine provided with a chute, and a reciprocating escapement for the said tacks, said magazine being operated by said oscillating lever, said tack escapement being controlled by said oscillating lever, and said magazine and said last mentioned escapement being capable of manual operation independent of the operation of said oscillating lever.

6. In a button attaching machine, a plunger, a hopper provided with a chute for the reception of the button heads, an oscillating lever for operating said plunger, an escapement on said chute, said oscillating lever actuating said hopper and reciprocating said escapement, said escapement being capable of manual operation independently of said oscillating lever, a rotatable tack magazine operated by said oscillating lever and provided with a chute, a reciprocating escapement controlled by said oscillating lever and means operable manually and independent of said oscillating lever for simultaneously rotating said tack magazine and reciprocating said tack escapement to thereby feed successive tacks beneath the plunger.

45. 7. A button attaching machine comprising in part a plunger and an oscillating lever for operating the same, a tack magazine having a chute extending therefrom, a table at the lower end of said chute, tack-receiving jaws at the end of said table and positioned beneath the said plunger, a tucker mechanism and an escapement mechanism, the said tucker mechanism being cooperatively associated with said escapement mechanism and the said oscillating lever controlling the movement of the said hopper, escapement and tucker mechanism, and means independently operable of the said oscillating lever for rotating the tack hopper, moving the tucker slide and oscillating the escapement, to thereby cause the tucker slide to force a tack across the table to the tack receiving jaws.

60. 8. A button attaching machine comprising in part a plunger and an oscillating

lever for operating the same, a tack feeding means comprising a rotatable hopper provided with a chute, an escapement mounted on said chute, a tucker mechanism cooperating with said escapement, a table at the end of said chute, tack-receiving jaws at the end of said table and under said plunger, all of said tack feeding means synchronized and operable by the said oscillating lever, and means for operating all of the said tack feeding means manually and independently of the said oscillating lever.

9. A button attaching machine comprising in part a plunger and means for operating the same, a hopper, a chute extending from said hopper, a table located at the lower end of said chute, tack-receiving jaws at the end of said table and beneath said plunger, an escapement on said chute, a tucker mechanism cooperating with said escapement to normally lock the same, said oscillating lever operating said tucker mechanism to thereby release a tack by movement of said escapement and feed the tack across the table to the tack-receiving jaws, and means for manually operating the tucker mechanism independently of the movement of the oscillating lever.

10. A button attaching machine comprising in part a plunger and means for operating the same, a rotatable tack magazine and a chute extending from the same, a table located at the lower end of said chute, tack-receiving jaws at the end of said table and beneath said plunger, a reciprocating tack escapement on said chute, a tucker mechanism connected with said escapement to normally hold the same in locked position during the major portion of the movement of the tucker mechanism, and an oscillating lever connected to said tucker mechanism to thereby rotate said hopper and operate said tucker mechanism to thus unlock the escapement and cause the tucker mechanism to feed the tacks across the table to the tack receiving jaws.

11. A button attaching machine comprising in part a plunger and means for operating the same, a rotatable tack magazine and a chute extending from the same, a table located at the lower end of said chute, tack-receiving jaws at the end of said table and beneath said plunger, a reciprocating tack escapement on said chute, a tucker mechanism connected with said escapement to normally hold the same in locked position during the major portion of the movement of the tucker mechanism, an oscillating lever connected to said tucker mechanism to thereby rotate said hopper and operate said tucker mechanism to thus unlock the escapement and cause the tucker mechanism to feed the tacks across the table to the tack receiving jaws, and means for manually operating the hopper and tucker

mechanism independently of the oscillating lever.

12. A button attaching machine comprising in part a plunger, and oscillating lever for operating said plunger, a second oscillating lever connected to said first oscillating lever, tack receiving and supplying means comprising a hopper provided with a chute, a reciprocating escapement for said chute, a tucker mechanism operably connected with said escapement for oscillating the same, means for adjusting the throw of the escapement, a table located at the lower end of the chute, tack receiving jaws at the end of the table, and means connected with the second oscillating lever for rotating the hopper and operating the tucker mechanism to thereby feed the tack across the table to the tack receiving jaws. 70
13. A button attaching machine comprising in part a plunger, an oscillating lever for operating said plunger, a second oscillating lever connected to said first oscillating lever, tack receiving and supplying means comprising a hopper provided with a chute, a reciprocating escapement for said chute, a tucker mechanism operably connected with said escapement for oscillating the same, means for adjusting the throw of the escapement, a table located at the lower end of the chute, tack-receiving jaws at the end of the table, means connected with the second oscillating lever for rotating the hopper and operating the tucker mechanism to thereby feed the tack across the table to the tack-receiving jaws, and means manually operable independently of the second oscillating lever for operating the tucker mechanism and thus the escapement and cause the tucker to force the tack to the tack receiving jaws. 80
14. In a button attaching machine a plunger, an oscillating lever for moving the same, a second lever operated by said first mentioned lever, the second lever provided with a bearing at its lower end, a suitably mounted bell crank, a pitman provided with a cross head thereon, said cross head mounted in said bearing, a feeding mechanism comprising in part an escapement for the tacks, and a tucker mechanism operably connected with the escapement, said tucker and escapement being operated normally by the movement of said pitman through the operation of said second lever and said pitman being independently operable of said lever by a manual movement of said bell crank to thereby operate the tucker slide and escapement. 90
15. In a button attaching machine, a plunger, an oscillating lever for moving the same, a second oscillating lever operably connected with said first mentioned lever, a yoke secured to the lower end of said second oscillating lever and a cross head mounted therein, a spring-pressed pitman secured in said yoke, a bell crank lever provided with a handle, a head on the forward end of said pitman and pivotally connected to said bell crank, a tack feeding mechanism comprising a rotatable hopper, means connected with the head on said pitman for rotating said hopper, a chute extending from said hopper, an escapement on said chute, and a tucker mechanism connected to said escapement, said tucker mechanism pivotally connected to said bell crank, the second oscillating lever normally operating said pitman to operate the hopper, escapement and tucker mechanism, and a movement of the bell crank by said handle forcing the pitman through said cross head and independently operating said tack feeding mechanism. 100
16. In a button attaching machine, a plunger, an oscillating lever for moving the same, a fulcrumed second oscillating lever operated by said first mentioned lever, a yoke at the lower end of said oscillating lever, a cross head mounted in said yoke, an adjustable pitman in said cross head, a suitably mounted bell crank lever, a head secured to the forward end of said pitman and pivotally mounted to said bell crank, a tack feeding mechanism comprising a rotatable hopper and chute, means connected to the forward end of the pitman and rotatable hopper for revolving said hopper when said bell crank lever is operated, an escapement and tucker mechanism connected therewith, said tucker mechanism also connected to said bell crank, a handle on said bell crank, and a spring on said pitman located between the cross head and the forward head on said pitman, the bell crank being normally operated by the operation of said oscillating lever to thereby operate the tack feeding mechanism, the said pitman being capable of movement through said cross head by a manual operation of the bell crank to thereby operate the said tack feeding mechanisms and the spring returning the pitman and bell crank to its normal position. 110
17. In a button attaching machine, a tack feeding mechanism comprising a rotatable hopper and chute, an escapement on said chute, a tucker mechanism cooperatively connected with said escapement, a bell crank, the tucker mechanism pivotally connected to said bell crank, means connecting the rotatable hopper with said bell crank, automatic means for operating the bell crank to operate the feeding mechanism, and manual means for independently operating the bell crank to thereby operate the feeding mechanism. 120
18. In a button attaching machine, a plunger, an oscillating lever connected therewith, a second oscillating lever oper- 130

ated by said first mentioned lever, a tack feeding mechanism comprising a rotatable hopper and a chute, a table at the lower end of the chute, tack receiving jaws at the 5 end of the table, a tucker slide, an escapement on said chute connected with the tucker slide, a bell crank lever operably connected with said tucker slide and with said rotatable hopper, means connecting 10 said second oscillating lever with said bell crank to automatically rotate said hopper and operate said tucker slide, and means on said bell crank for manually moving the same to thereby release a tack and force 15 the same to the tack receiving jaws.

19. In a button attaching machine, a plunger, means for operating the same, a tack feeding mechanism comprising a rotatable hopper and chute, a table at the end 20 of the chute, tack receiving jaws at the end of the table and beneath the plunger, an escapement, a tucker slide locking said escapement and regulating the movement thereof, a bell crank lever operably connected with 25 the rotatable chute and tucker slide, means connected with the means for operating the plunger for automatically operating the hopper and tucker slide, and manual means for operating the bell crank independently 30 of the means for moving the plunger, to thereby feed a tack to the tack receiving jaws.

20. A button attaching machine comprising in part a tucker mechanism and an escapement mechanism, a bell crank extending 35 between the same, means on said bell crank cooperating with the tucker slide to lock the escapement against movement until said tucker slide has moved to its rearward- 40 most limit.

21. A button attaching machine comprising in part a tucker mechanism and an escapement mechanism, a suitably mounted crank, a rod connected to said escapement 45 and operated by said crank to thereby operate said escapement, a locking finger forming a part of said crank, and a portion of the tucker mechanism contacting with said locking finger to thereby lock the crank and 50 escapement against movement until the tucker slide moves to such a position as to release said locking finger.

22. A button attaching machine comprising in part a tucker mechanism and an escapement mechanism, a suitably mounted 55 crank, a rod connected to said escapement and operated by said crank to thereby operate said escapement, a locking finger forming a part of said crank, a portion of the tucker mechanism contacting with said locking finger to thereby lock the crank and 60 escapement against movement until the tucker slide moves to such a position as to release said locking finger, means for automatically moving said tucker mechanism, 65

and means for manually implying movement to said tucker slide.

23. A button attaching machine comprising in part a tucker mechanism and an escapement mechanism, a suitably mounted 70 crank, a rod connected to said escapement and operated by said crank to thereby operate said escapement, a locking finger forming a part of said crank, a portion of the tucker mechanism contacting with said locking finger to thereby lock the crank and escapement against movement until the tucker slide moves to such a position as to 75 release said locking finger, and means for automatically imparting movement to said tucker mechanism, said means being capable of a manual independent operation. 80

24. A button attaching machine comprising in part a tucker mechanism and an escapement mechanism, a suitably mounted 85 crank, an adjustable rod connected to said escapement and operated by said crank to thereby operate said escapement, a locking finger forming the lower portion of said crank having a hook at its rear end, and a 90 roller on said tucker mechanism contacting with said locking finger to thereby lock the crank and escapement against movement until the tucker slide moves rearwardly and said roller contacts with said hook to thereby release the locking finger and to move the rod on said escapement to thereby operate 95 the latter.

25. A button attaching machine having a tack feeding mechanism comprising in part 100 an escapement mechanism, a tucker mechanism normally tightly locking said escapement mechanism against movement, and automatic means for moving said tucker slide and unlocking the escapement mechanism. 105

26. A button attaching machine having a tack feeding mechanism comprising in part an escapement mechanism, a tucker mechanism normally tightly locking said escapement mechanism against movement, automatic means for moving said tucker slide and unlocking the escapement mechanism, and means for manually operating said 110 automatic means. 115

27. In a button attaching machine, a tack feeding mechanism comprising in part a tucker mechanism, the said tucker mechanism comprising a casing having a groove formed therein in the form of an inverted 120 T and a tucker slide slidingly fitting within said groove and thereby held against canting during its movement, a downwardly extending arm formed on the undersurface of the tucker slide having rollers thereon to 125 contact with the undersurface of the casing to thereby additionally prevent the tucker slide from canting, a bell crank pivotally connected with said tucker slide for automatically moving the same. 130

28. In a button attaching machine, a tack feeding mechanism comprising in part a tucker mechanism, the said tucker mechanism comprising a casing having a groove 5 formed therein in the form of an inverted T and a tucker slide slidingly fitting within said groove and thereby held against canting during its movement, a downwardly extending arm formed on the undersurface of 10 the tucker slide having rollers thereon to contact with the undersurface of the casing to thereby additionally prevent the tucker slide from canting, and a bell crank pivotally connected with said tucker slide for 15 automatically moving the same, and said bell crank capable of a manual movement to thereby operate the tucker slide. 29. A button attaching machine having a tack feeding mechanism, the latter comprising 20 in part a tucker mechanism, the tucker mechanism comprising a casing having a slot formed therein, a tucker slide moving within said groove, a table and a portion of the tucker slide adapted to extend across the 25 table when operated, a downwardly extending arm forming a part of the tucker slide having rollers thereon, a finger on one side of the casing, and a crank having a complementary finger so that the rollers will 30 contact on the one side of the casing with the bottom surface of the casing and on the other side with a cam surface of the finger on the crank, the surface being parallel with the undersurface of the casing to thereby 35 prevent the tucker slide from canting. 30. A button attaching machine comprising 40 in part a tack feeding mechanism consisting of a hopper and chute, an oscillating escapement for said chute, a tucker mechanism, the said tucker mechanism comprising a casing provided with a groove therein and a tucker slide operating in said groove, a bell crank secured to said casing and one arm thereof having a finger extending along 45 the side of the tucker mechanism, another arm operatively connected to the escapement, rollers associated with the tucker slide and locking said finger throughout the greater portion of the movement of the tucker slide, 50 and means on said crank contacting with a roller as the tucker slide approaches its rearmost limit to thereby unlock the crank and throw the same off center to oscillate the escapement mechanism. 55 31. A button attaching machine comprising 60 in part a tack feeding mechanism, consisting of a hopper and chute, an oscillating escapement for said chute, and a tucker mechanism normally locking said escapement against movement, said locking means comprising a crank and a rod extending between one arm of the crank and pivotally secured to said oscillating mechanism, the 65 lower portion of the crank being provided with a cam finger and a hook at its rear end, the tucker slide having rollers thereon one of which travels along the locking finger and abuts against the hook as it approaches its rearmost limit to thereby unlock the finger and force the rod downwardly to thereby oscillate the escapement. 70 32. A button attaching machine comprising 75 in part a tack feeding mechanism, consisting of a hopper and chute, an oscillating escapement for said chute, a tucker mechanism normally locking said escapement against movement, said locking means comprising a crank and a rod extending between one arm of the crank and pivotally secured to said oscillating mechanism, the 80 lower portion of the crank being provided with a cam finger and a hook at its rear end, the tucker slide having rollers thereon one of which travels along the locking finger and abuts against the hook as it approaches its rearmost limit to thereby unlock the finger and force the rod downwardly to thereby oscillate the escapement, and means 85 to automatically operate said tucker slide to thereby feed the tacks. 33. A button attaching machine comprising 90 in part a tack feeding mechanism, consisting of a hopper and chute, an oscillating escapement for said chute, a tucker mechanism normally locking said escapement against movement, said locking means comprising a crank and a rod extending between one arm of the crank and pivotally secured to said oscillating mechanism, the 95 lower portion of the crank being provided with a cam finger and a hook at its rear end, the tucker slide having rollers thereon one of which travels along the locking finger and abuts against the hook as it approaches its rearmost limit to thereby unlock the finger and force the rod downwardly to thereby oscillate the escapement, and means to automatically operate said tucker slide to thereby feed the tacks. 100 34. A button attaching machine comprising 105 in part a tack feeding mechanism, consisting of a hopper and chute, an oscillating escapement for said chute, a tucker mechanism normally locking said escapement against movement, said locking means comprising a crank and a rod extending between one arm of the crank and pivotally secured to said oscillating mechanism, the 110 lower portion of the crank being provided with a cam finger and a hook at its rear end, the tucker slide having rollers thereon, one of which travels along the locking finger and abuts against the hook as it approaches its rearmost limit to thereby unlock the finger and force the rod downwardly to thereby oscillate the escapement, and means to automatically operate said tucker slide to thereby feed the tacks, said automatic means also capable of a manual movement. 115 35. A button attaching machine comprising 120 in part a tack feeding mechanism, consisting of a hopper and chute, an oscillating escapement for said chute, a tucker mechanism normally locking said escapement against movement, said locking means comprising a crank and a rod extending between one arm of the crank and pivotally secured to said oscillating mechanism, the 125 lower portion of the crank being provided with a cam finger and a hook at its rear end, the tucker slide having rollers thereon, one of which travels along the locking finger and abuts against the hook as it approaches its rearmost limit to thereby unlock the finger and force the rod downwardly to thereby oscillate the escapement, means for manually forcing said tucker slide rearwardly to thereby oscillate the escapement, and means arranged to normally and auto- 130

matically return the tucker slide to its foremost position and thereby again oscillate the escapement.

35. A button attaching machine comprising in part a tack feeding mechanism having a rotatable hopper, a chute extending therefrom, an oscillating escapement across the chute, a tucker mechanism and a lock extending between the tucker mechanism and the oscillating escapement, the lock comprising a rod having an adjustable sleeve thereon, a collar on the rod, a bearing pivotally mounted on the escapement and a spring between the collar and the bearing, 10 and the oscillating escapement, the lock comprising a rod having an adjustable sleeve thereon, a collar on the rod, a bearing pivotally mounted on the escapement and a spring between the collar and the bearing, 15 a crank arm contacting with said collar, the lower part of the crank having a cam finger and hook at its rear end, a roller connected with the tucker slide normally holding the finger upwardly to thereby lock the rod of 20 the escapement against movement, means for operating the tucker slide rearwardly to unlock the said finger as the tucker slide approaches its rearmost limit, the upper portion of the arm pressing the collar on the 25 rod downwardly to thereby oscillate the escapement, and means for returning the tucker slide to its forwardmost position to thereby oscillate the escapement and hold it in its locked position.
- 30 36. A button attaching machine comprising in part a tack feeding mechanism consisting of a chute, an escapement capable of oscillating across said chute, a slidable rod pivotally connected to said escapement, 35 an adjustable sleeve on said rod, a collar on said rod and abutting against said sleeve, a spring extending between the escapement and said collar, a tucker slide, a crank operated by said tucker slide, one end of the 40 crank contacting with said sleeve and said collar, and means for operating the tucker slide to thereby cause the crank to force the rod connected with the escapement to move downwardly to oscillate the escapement, 45 while the continued movement of the crank arm will cause the collar to compress the spring to thereby receive the strain on the escapement.

37. A button attaching machine comprising in part a tack feeding mechanism consisting of a chute, an escapement capable of oscillating across said chute, a slidable rod pivotally connected to said escapement, an adjustable sleeve on 50 said rod, a collar on said rod and abutting against said sleeve, a spring extending between the escapement and the said collar, a tucker slide, a crank operated by said tucker slide, one end of the crank contacting with 55 said sleeve and said collar, and automatic means for operating the tucker slide to thereby cause the crank to force the rod connected with the escapement to move downwardly to oscillate the escapement, while the 60 continued movement of the crank arm will

cause the collar to compress the spring to thereby receive the strain on the escapement.

38. A button attaching machine comprising in part a tack feeding mechanism consisting of a chute, an escapement capable of 70 oscillating across said chute, a slidable rod pivotally connected to said escapement, an adjustable sleeve on said rod, a collar on said rod and abutting against said sleeve, a spring extending between the escapement 75 and said collar, a tucker slide, a crank operated by said tucker slide, one end of the crank contacting with said sleeve and said collar, automatic means for operating the tucker slide to thereby cause the crank to 80 force the rod connected with the escapement to move downwardly to oscillate the escapement, while the continued movement of the crank arm will cause the collar to compress the spring to thereby receive the strain on the escapement, means for manually moving the tucker slide rearwardly, and spring means for returning the tucker slide to its forwardmost position and oscillating the escapement as the tucker starts its forward 85 movement.

39. A button attaching machine comprising a tack feeding mechanism, the said tack feeding mechanism comprising a rotatable hopper and a chute, an oscillating escapement pivotally mounted to said chute, a table at the lower end of said chute and tack receiving jaws at the end of the table, a tucker mechanism normally locking said escapement and controlling the movement of said escapement, a movable angularly extending arm forming the lower part of said chute on its one side, a horizontally movable arm mounted on said table, a plate opposite said second arm both forming a guideway for a tack across the table, and means for operating the tack mechanism to release a tack and force it across the table to the tack receiving jaws.

40. A button attaching machine comprising a tack feeding mechanism, the said tack feeding mechanism comprising a rotatable hopper and chute, an oscillating escapement pivotally mounted on said chute, a table at the lower end of said chute, tack receiving jaws at the end of the table, a tucker mechanism, an escapement on said chute, the said tucker mechanism normally locking said escapement and controlling the entire movement of said escapement, a movable arm forming the lower part of said chute on its one side, means on said table for forming a passageway for the tack across the table, one of said means being free to swing, and means for operating the tucker, said means also connected to said hopper to rotate the same.

41. A button attaching machine comprising a tack feeding mechanism, the said tack feeding mechanism comprising a rotatable

- hopper and chute, an oscillating escapement pivotally mounted on said chute, a table at the lower end of said chute, tack receiving jaws at the end of the table, a tucker mechanism, an escapement on said chute, the said tucker mechanism normally locking said escapement and controlling the entire movement of said escapement, a movable arm forming the lower part of said chute on its 5 one side, means on said table for forming a passageway for the tack across the table, one of said means being free to swing, and means for operating the tucker, said means being connected to said hopper to rotate the 10 same and capable of a manual operation to rotate the hopper and operate the tucker slide.
42. A button attaching machine comprising a tack feeding mechanism, the said tack feeding mechanism comprising a rotatable hopper and chute, an oscillating escapement pivotally mounted on said chute, a table at the lower end on said chute, tack receiving jaws at the end of the table, a tucker mechanism, an escapement on said chute, the said tucker mechanism normally locking said escapement and controlling the entire movement of said escapement, a movable arm forming the lower part of said chute on its 15 one side, means on said table for forming a passageway for the tack across the table, one of said means being free to swing, and means for operating the tucker, said means being connected to said hopper to rotate the same and capable of a manual operation to rotate the hopper and operate the tucker slide, and said means returning the tucker slide and escapement to their normal positions.
43. In a button attaching machine, a tack feeding mechanism comprising a rotatable hopper and chute, an escapement adapted to oscillate across said chute, a tucker mechanism normally locking said escapement against oscillation, means for forcing the tucker slide rearwardly to thereby unlock the escapement and oscillate the same, means for adjusting the throw of the escapement to thereby synchronize the tucker slide and escapement, and means for automatically returning the tucker slide to thereby again oscillate the escapement and lock it against movement until the tucker slide is again moved rearwardly.
44. In a button attaching machine, a tack feeding mechanism comprising a rotatable hopper and chute, an escapement adapted to oscillate across said chute, a tucker mechanism operatively connected with said escapement, a bell crank lever for forcing the tucker slide rearwardly and to unlock the escapement and oscillate the same as the tucker slide approaches its rearwardmost limit of travel, means for adjusting the throw of the escapement and to take up the

wear to thereby synchronize the escapement with the movement of the tucker slide, and spring pressed means for normally returning the tucker slide to its forwardmost limit, the escapement being oscillated at the beginning of the forward movement of the tucker slide and locked against movement until the tucker slide again approaches its rearward limit.

45. In a button attaching machine, a tack feeding mechanism comprising a rotatable hopper and chute, an escapement adapted to oscillate across said chute, a tucker mechanism operatively connected with said escapement, a bell crank lever for forcing the tucker slide rearwardly and to unlock the escapement and oscillate the same as the tucker slide approaches its rearwardmost limit of travel, means for adjusting the throw of the escapement and to take up the wear to thereby synchronize the escapement with the movement of the tucker slide, spring pressed means for normally returning the tucker slide to its forwardmost limit, the escapement being oscillated at the beginning of the forward movement of the tucker slide and locked against movement until the tucker slide again approaches its rearward limit, and means for automatically operating the bell crank lever, said bell crank lever also capable of manual movement.

46. A button attaching machine comprising a plunger, an oscillating lever for operating the plunger, a tack feeding mechanism comprising a hopper and chute, jaws pivotally mounted to said chute and adapted to oscillate across the same to release a tack, a tucker slide, means connected to the tucker slide and to the jaws for oscillating the same when said tucker slide approaches its rearwardmost limit, means for regulating the forward limit of the tucker slide, and means for adjusting the oscillation limits of the jaws, said oscillating lever automatically operating the tack feeding mechanism.

47. A button attaching machine comprising a plunger, an oscillating lever for operating the plunger, a tack feeding mechanism comprising a hopper and chute, jaws pivotally mounted to said chute and adapted to oscillate across the same to release a tack, a tucker slide, means connected to the tucker slide and to the jaws for oscillating the same when said tucker slide approaches its rearward limit, means for regulating the forward limit of the tucker slide, means for adjusting the oscillation limits of the jaws, said oscillating lever automatically operating the tack feeding mechanism, and means for operating the tack feeding mechanism independently of the movement of said oscillating lever.

48. In a button attaching machine, a

- plunger, an oscillating lever for operating the same, automatic means for feeding a button to the plunger, said automatic means being capable of a manual operation, a tack feeding mechanism comprising a hopper and chute, an escapement, a tucker mechanism, tack receiving jaws, a locking means between said tucker mechanism and said escapement, and a bell crank, said oscillating lever being connected with said bell crank to operate the entire tack feeding mechanism and the tack feeding mechanism being synchronized with the button feeding mechanism.
- 15 49. In a button attaching machine, a plunger, an oscillating lever for operating the same, automatic means for feeding a

button to the plunger, said automatic means being capable of a manual operation, a tack feeding mechanism comprising a hopper 20 and chute, an escapement, a tucker mechanism, tack receiving jaws, a locking means between said tucker mechanism and said escapement, a bell crank, said oscillating lever being connected with said bell crank to 25 operate the entire tack feeding mechanism and the tack feeding mechanism being synchronized with the button feeding mechanism, and means for manually operating the bell crank to feed additional tacks 30 to the tack receiving jaws.

In testimony whereof I affix my signature.

FRANKLIN R. WHITE.
